UNITED STATES PATENT OFFICE.

ELMER J. RYAN, OF LONG BEACH, CALIFORNIA, ASSIGNOR OF ONE-FOURTH TO PRUDENCE M. WELSH AND ONE-FOURTH TO MARVIN H. DARBY, BOTH OF LONG BEACH, CALIFORNIA.

DESIGN FOR A MATCH-SCRATCHER.

47,250.

Specification for Design.

Patented Apr. 20, 1915.

Application filed December 22, 1914. Serial No. 878,622. Term of patent 3½ years.

To all whom it may concern:

Be it known that I, ELMER J. RYAN, a citizen of the United States, residing at Long Beach, in the county of Los Angeles and State of California, have invented a new, original, and ornamental Design for a Match-Scratcher, of which the following is a specification, reference being had to the accompanying drawing, forming part thereof.

Figure 1 is a front elevation of the match

scratcher. Fig. 2 is a longitudinal sectional view therethrough. Fig. 3 is a rear elevation.

I claim:

The ornamental design for a match scratcher, as shown.

ELMER J. RYAN.
